UNITED STATES PATENT OFFICE.

EDWIN S. PRIDHAM AND PETER L. JENSEN, OF OAKLAND, CALIFORNIA, ASSIGNORS TO THE MAGNAVOX COMPANY, OF OAKLAND, CALIFORNIA, A CORPORATION OF ARIZONA.

ELECTRODYNAMIC RECEIVER.

Application filed March 29, 1922. Serial No. 545,095.

To all whom it may concern:

Be it known that we, EDWIN S. PRIDHAM and PETER L. JENSEN, citizens of the United States, residing at Oakland, county of Alameda, and State of California, have invented new and useful Improvements in Electrodynamic Receivers, of which the following is a specification.

This invention relates to the manufacture and assembly of electro-dynamic receivers. The type of receiver under consideration is shown, for instance, in our application Serial No. 377,354, filed in the United States Patent Office April 28th, 1920, and is characterized by the use of an annular coil rigidly connected to a diaphragm and disposed concentrically with relation to an axial and a circumferential pole piece so as to be freely movable in a strong magnetic field.

The object of this invention is to facilitate the manufacture and assembly of a receiver of this type whereby to insure in a simple and ready manner the correct positioning of the movable coil.

Referring to the accompanying drawing—

Fig. 1 shows a side elevation, partly in section, of a receiver embodying our invention.

Fig. 2 shows a diagrammatic view of the enclosing casing and circumferential pole piece, the latter forming a cover for the casing.

Fig. 3 shows a diagrammatic view in section of the circumferential pole piece and base plate of the sound box in position upon a flanged gauge whereby to correctly position these parts in assembling.

Fig. 4 shows a sectional view of the circumferential pole piece and diaphragm illustrating the manner of positioning the movable coil concentrically within the circumferential pole piece.

The device includes a receiver head assembly and an electro-magnetic structure. The receiver head assembly consists of a sound box A, a movable coil B and a circumferential pole piece C adapted to be placed upon the magnetic structure. The electro-magnetic structure consists of an iron cylinder D containing a magnetic coil E wound upon a core F, which forms one of the pole pieces.

In the manufacture and assembly of these

parts it is of the greatest importance that the coil B be correctly centered with relation to the pole pieces C and F. In other words, this movable coil must be exactly concentric therewith and equally spaced therefrom. To bring this about in a simple and ready manner we first gauge the cylinder and then place the core F therein and center it by means of a spacing disc 10 of insulating material. The circumferential pole piece C, which forms the cover for the cylinder, is provided with a shoulder or recess 11 which is gauged to fit the cylinder D and a central opening 12 is cut therein so that it is exactly concentric with the core F, leaving a true concentric space between. The sound box 70 is next assembled upon the circumferential pole piece. It will be noted that the sound box comprises a base plate 13, a diaphragm 14 and a top portion 15. The base plate has a central aperture 16 and the correct position of the base plate upon the circumferential pole piece is obtained by means of a flanged gauge 17. This gauge has a stem 18 to exactly fit the central opening in the circumferential pole piece and a flange 19 to fit the opening in the base plate. When the base plate is thus positioned, it is attached to the pole piece by means of screws 20.

Next the coil B is put in position on the connected pole piece and base plate. Previously the coil is attached to the diaphragm 14 by brackets 21. A cylindrical gauge 22 having walls of a thinness corresponding to the required space between the circumferential pole piece and coil is positioned in the central opening in the circumferential pole piece and the coil is then inserted in the cylindrical gauge, thereby insuring correct positioning of the coil. Thereafter the diaphragm is attached to the base plate and the two pole pieces having been properly gauged, it is assured that the coil will occupy a true concentric position equally spaced from each of the pole pieces when the receiver head assembly is placed upon the magnetic structure.

Having thus described our invention, what we claim and desire to secure by Letters Patent is:

1. In the manufacture of an electro-dynamic receiver of the type having a cylindrical casing containing an axial pole piece with

- a circumferential pole piece surrounding the axial pole piece and a movable coil carried upon the diaphragm of a sound box disposed concentrically between the pole pieces, the 5 steps of centering the axial pole piece within the casing by means of a spacing ring fitted against the axial pole piece and the casing above the coil surrounding the said axial pole piece, gauging the circumferential pole piece to fit the cylindrical casing, forming a circular aperture at the center of the circumferential pole piece and setting the movable coil in place within said aperture by means of a cylindrical gauge removably placed between the coil and the walls of the circumferential pole piece.
2. In the manufacture of an electro-dynamic receiver having a cylindrical casing containing an axial pole piece with a circumferential pole piece surrounding the axial pole piece and a movable coil carried upon the diaphragm of a sound box disposed between the two pole pieces, the steps of recessing the circumferential pole piece to fit the cylindrical casing, providing the circumferential pole piece with a circular aperture centered with respect to the recess thereon, centering the axial pole piece within the cylindrical casing by means of a spacing ring fitted against the axial pole piece and the casing above the coil surrounding the said axial pole piece and positioning the movable coil by means of a cylindrical gauge removably fitted within the circular aperture in the circumferential pole piece.
3. In the manufacture of an electro-dynamic receiver having a cylindrical casing

containing an axial pole piece with a circumferential pole piece surrounding the axial pole piece and a movable coil carried upon the diaphragm of a sound box disposed between the two pole pieces, the steps of recessing the circumferential pole pieces to fit the cylindrical casing and providing said pole piece with a circular aperture centered with respect to the recess, centering the axial pole piece within the cylinder by means of a spacing ring, positioning the frame of the sound box upon the circumferential pole piece by means of a flanged gauge and thereafter positioning the movable coil with its connected diaphragm by means of a cylindrical gauge fitted within the central opening in the circumferential pole piece.

4. An article of manufacture comprising 55 an electromagnetic structure including a cylinder, an axial pole piece within the cylinder, a magnetic coil wound upon the pole piece and seated upon the bottom of the casing, a receiver head assembly detachably 60 fitted upon said cylinder and comprising a circumferential pole piece forming a cover plate for the cylinder, a sound box mounted upon the circumferential pole piece, a movable coil fixed to the diaphragm of the sound box and arranged concentrically between the two pole pieces, and a spacing disc arranged between the axial pole piece and the cylinder and located above the magnetic coil to position said pole piece concentrically 65 therewith.

EDWIN S. PRIDHAM.
